UNITED STATES PATENT OFFICE.

JACOB C. WOLFE, OF NEW YORK, N. Y.

BACKING FOR ELECTROTYPE OR STEREOTYPE SHELLS.

SPECIFICATION forming part of Letters Patent No. 447,626, dated March 3, 1891.

Application filed February 14, 1890. Serial No. 340,423. (No model.)

To all whom it may concern:

Be it known that I, JACOB C. WOLFE, of New York city, in the county and State of York, have invented a new and Improved 5 Backing for Electrotype or Stereotype Shells, of which the following is a full, clear, and exact description.

My invention relates to the backing of electrotype or stereotype shells, and has for its 10 object to accomplish the same in a simple and expeditious manner and to provide a backing with straight sides and ends and of the least possible weight.

The invention consists in the novel construction and combination of the several parts, 15 as will be hereinafter fully set forth, and pointed out in the claims.

Reference is to be had to the accompanying drawings, forming a part of this specification, 20 in which similar figures of reference indicate corresponding parts in all the views.

Figure 1 is a central vertical section through a shell, its backing, and guide-frame, the same being illustrated as located in a 25 press. Fig. 2 is a side elevation of the backing and a shell attached thereto. Fig. 3 is a perspective view of the backing. Fig. 4 is a perspective view of the guide-frame. Fig. 5 is a perspective view of a slightly-modified 30 form of backing, and Fig. 6 is a transverse section of Fig. 5.

The backing 10 is made preferably of metal, and is ordinarily cast or forged in box form, as shown in Fig. 3, the said box comprising 35 end pieces, side pieces, and a top 11, the bottom being open and the interior of the backing hollow, and the said top 11 is provided with a series of perforations or apertures 12. This form of backing is used when medium 40 or large-sized shells are to be backed; but the backing of very narrow and long shells is constructed as shown in Fig. 5, in which the top face 11, instead of being perforated, is provided with one or more longitudinal 45 grooves or channels 13, and the under side is recessed longitudinally in order to lighten the block constituting the backing. The grooves or channels 13 in the form of backing shown in Fig. 5 and the apertures or perforations in that form illustrated in Fig. 3 50 may be properly termed "vents."

In connection with the backing and the shell

14 a guide-frame 15 is employed, which is open at top and bottom and closed at the sides and ends, and the size of the said frame is made 55 to correspond with the size of the shell to be backed. I further use in connection with the backing and shell a press of any suitable or approved construction, one form that may be employed being illustrated in Fig. 1, and consisting of a base 16, having a smooth straight upper surface, and from the corners of the base rods 17 are upwardly projected, provided near their upper extremities with a flange 18, and a thumb 19 is screwed upon the upper 60 extremity of each of the rods.

It will be readily observed that but little, if any, of the cementing material need remain between the smooth surface of the backing and shell, since the cement passing through 70 the perforations forms in buttons upon the inner side of the backing and effectually binds the shell to place. A top plate 20 is also employed, provided with apertures in its corners, through which the threaded portions of 75 the rods extend, and the said thumb-nuts have a bearing upon this top plate. The distance between the upper face of the base 16 and the upper surface of the flanges 18 corresponds to the height of a type, with which 80 type the height of the combined backing and shell must correspond.

In operation, to back a shell, the shell 14 is placed face downward within the guide-frame 85 15, which guide-frame is located upon the upper surface of the base 16 of the press or other equivalent support. Before the shell is placed in its guide-frame it is heated, and upon the upper face of the shell, which is the under face in use, a fusible metal solder 21 is placed, 90 such as tin-foil, which solder or fusible material is made to cover the entire surface of the shell, and is placed on in sufficient quantities to render the combined backing and shell more than type-high when the former is 95 placed upon the latter. The backing 10 is also heated, and its grooved or apertured top is brought in contact with the solder or fusible metal upon the shell. The top plate or its equivalent of the press is then applied to 100 the bottom of the backing, and the said top plate is carried downward under pressure until the shell and its backing are exactly type-high.

The vents in the top of the backing are provided in order that the surplus cementing material may find an escape as the backing is evenly and gradually pressed downward.

5 When cooled, the backing is removed from the guide-frame, and the shell will be found to be evenly and firmly cemented thereto. The backing, which, as heretofore stated, is preferably in the nature of a shell and box-like in form, is provided with perpendicular smooth end and side surfaces.

Having thus described my invention, I claim as new and desire to secure by Letters Patent—

15 1. The combination, with an electrotype or

stereotype shell, of a backing provided with vents and a space above the vents for the reception of the surplus cementing material passing through said vents, substantially as herein shown and described.

2. The combination, with electrotype or stereotype shells, of a metal box-like backing having vents produced in one face for the reception of the surplus cementing material, by which the shell is secured to the backing, substantially as shown and described.

20 JACOB C. WOLFE.
